UNITED STATES PATENT OFFICE

155,170

DESIGN FOR A WET AND DRY BULB
THERMOMETER ASSEMBLYAnthony H. Lamb, Hillside, N. J., assignor to
Weston Electrical Instrument Corporation,
Newark, N. J., a corporation of New Jersey

Application December 8, 1947, Serial No. 143,039

Term of patent 14 years

(Cl. D52—7)

To all whom it may concern:

Be it known that I, Anthony H. Lamb, a citizen of the United States, residing at Hillside, Union County, New Jersey, have invented a new, original, and ornamental Design for a Wet and Dry Bulb Thermometer Assembly, of which the following is a specification, reference being had to the accompanying drawings, forming part hereof, and wherein:

Fig. 1 is a face view of a wet and dry bulb thermometer assembly, showing my new design, the view being taken from a point in front of and above the assembly;

Fig. 2 is a perspective view of the same as seen from a point above and to the right of the assembly; and

Fig. 3 is a perspective view of the same as seen from a lower point and at the right of the assembly.

I claim:

The ornamental design for a wet and dry bulb thermometer assembly, as shown.

ANTHONY H. LAMB.
